UNITED STATES PATENT OFFICE.

ISRAEL MARCUS, OF WINTHROP, MASSACHUSETTS.

RENEWABLE FUSE.

Application filed February 13, 1919. Serial No. 276,783.

To all whom it may concern:

Be it known that I, ISRAEL MARCUS, a citizen of the United States, residing at Winthrop, in the county of Suffolk and State of Massachusetts, have invented certain new and useful Improvements in Renewable Fuses; and I do declare the following to be a full, clear, and exact description of the invention, such as will enable others skilled in the art to which it appertains to make and use the same.

The present invention relates to improvements in fuses used in electric circuits to protect the several loads thereon and the generator in case of short circuit to any particular load or if the strength of the current is suddenly increased from any other cause.

One object of the invention is to provide a quickly and easily renewable fuse having few parts when opened for the installation of a new fuse wire.

Another object is to decrease the flash when the fuse blows and to allow the generated gases but no flame to escape.

25 A further object is to provide a fuse having a resistance wire to act after blowing of the fuse wire, as a substitute for the resistance previously offered by any load in the circuit which may have been negatived by short circuit or other cause, thereby allowing other loads on the circuit to continue to operate.

With the foregoing objects in view, the invention resides in the novel features of construction and unique association of parts hereinafter fully described and claimed, and shown in the accompanying drawings.

Figure 1 is a side elevation of the improved fuse.

40 Fig. 2 is a similar view with the caps, on the ends of the fuse body, in section.

Fig. 3 is a longitudinal section of the entire fuse.

Fig. 4 is a similar view of the insulation body.

Fig. 5 is a second longitudinal section as indicated by the line 5—5 of Fig. 3.

55 Figs. 6, 7, 8 and 9 are transverse sections on the planes of the lines 6—6, 7—7, 8—8 and 9—9 respectively of Fig. 5.

In the drawings above briefly described, the numeral 1 designates an elongated preferably cylindrical body of insulation having screw threads 2 on its end portions and provided with a longitudinal recess 3 in one side, the ends of said recess extending into

the threads 2 as shown clearly in Figs. 2, 3 and 4. A pair of L-shaped contact plates 4 pass through passages 5 in the ends of the body 1 and project into the ends of a cavity 6 formed in the bottom wall of the recess 3, the short ends 7 of the contact plates 4 being preferably inserted in recesses 8 in the ends of the body 1.

A suitable fuse wire 9, preferably though not necessarily of flat formation, is removably secured by screws or the like 10 against the inner ends of the contact plates 4, and a high resistance wire 11 connects the ends of the fuse to take the load from the fuse when the latter blows. This has a number of advantages to be hereinafter fully set forth. The resistance wire 11 is located in a channel 12 formed in the bottom wall of the recess 3 and is thus segregated from the fuse wire 9.

An insert 13 of insulation is removably received in the recess 3 and is provided on its ends with screw threads 14 coinciding with the threads 2, and a pair of caps 15 of any preferred material are threaded over the ends of the body 1 and said insert 13. This secures the insert snugly in place, yet by unscrewing the caps 15 until the ends of the insert are freed, said insert may be quickly and easily removed to permit the installation of a new fuse wire. Particular emphasis is laid upon the fact that the caps 15 need not be entirely removed and thus there will be considerably less trouble and expenditure of time.

The outer ends of the caps 15 are formed with openings 16 through which terminals 17 pass, the inner ends of said terminals having contact plates 18 abutting the short arms 7 of the plates 4, said plates 18 being held in proper engagement with the arms 7 by washers 19 against which the ends of the caps bear. Each terminal 17 is preferably formed of a single strip of metal folded upon itself with its ends bent outward in opposite directions to form the contact plates 18, and to insure proper relation of said terminals with the body 1 at all times, certain of the plates 18 are provided with lugs 20 receivable in sockets 21 in the ends of the body 1.

The fuse is installed in the usual manner and when the circuit is operating under normal load, the fuse wire will serve as the conductor of the current. If a load or resistance in the circuit however should be short circuited or otherwise negatived in such a man-

ner as to direct a surplus of current through the other loads, the fuse wire 9 will immediately blow. The moment this blowing occurred, there would be a tremendous flash 5 and generation of gases, were it not for the high resistance wire 11. This wire, however, takes some load from the fuse to decrease the flash, but immediately after blowing of the main fuse 9, the wire 11 becomes 10 red-hot and blows also.

In order to insert a new fuse wire, it is simply necessary to partly unscrew the caps 15, remove the insert 13, detach the old fuse wire by removal of the screws 10, and to then 15 install the new fuse wire. As the resistance wire 11 is carried by the fuse wire, it will of course be renewed whenever the fuse wire is renewed.

Another feature which is by preference 20 employed, is the provision of openings 25 leading to the periphery of the body 1 from the cavity 6, said openings being of zig-zag form and serving to permit the escape of the generated gases when the fuse wire blows, 25 although not allowing any flame to escape.

Still another feature which may be employed, is the provision of flanges 26 arranged one on the insert 13 and one on the body 1 for reception in the groove 27 with 30 which said body and insert are provided (see Fig. 6). By this arrangement, the insert and body may be quickly centered for threading of the caps 15 over the ends of the former.

From the foregoing, taken in connection 35 with the accompanying drawings, it will be obvious that although the invention is of rather simple and inexpensive nature, it will be highly efficient and in every way desirable, 40 particular emphasis being laid upon the co-operation existing between the body 1, the insert 13, and the caps 15, upon the construction and arrangement of the terminals 17, upon the high resistance wire 11, and 45 upon the zig-zag openings 25. Since probably the best results are obtained from the precise arrangement shown and described, it may be followed, but within the scope of the invention as claimed numerous minor 50 changes may well be made, as occasion may dictate.

I claim:

1. A renewable fuse comprising an elongated body of insulation having threaded 55 end portions and provided in one side with a recess whose ends extend into said thread-

ed end portions of the body but terminate in spaced relation with the ends of the latter, a renewable fuse wire in said recess, an insert snugly received in said recess and having 60 threads on its ends coinciding with the threads of said body, caps threaded over the ends of said body and insert, and means for placing the ends of said fuse wire in electrical connection with the usual fuse clips. 65

2. A renewable fuse comprising an elongated body of insulation having threaded end portions and provided in one side with a recess whose ends extend into the threads of the body but terminate in spaced relation 70 with the ends of said body, the bottom wall of said recess having a fuse receiving cavity and the ends of said body being formed with longitudinal passages extending to the ends of said cavity, a pair of contact plates in 75 said passages having means at their inner ends for attaching a fuse thereto, the outer ends of said plates being exposed at the ends of said body, an insert in said recess, caps threaded on the ends of said body and extending over the ends of said insert, and terminals removable with said caps and normally in contact with said contact plates.

3. A device of the class described comprising an elongated body of insulation, a 80 pair of metallic contact plates at the ends of said body, a fuse in said body secured at its ends to said contact plates, a pair of caps secured on the ends of said body, said caps having openings, and terminals passing 85 through said openings, said terminals being each formed of a single strip of metal bent upon itself with its ends bent laterally within its respective cap to form contact plates 90 engaging said first named contact plates. 95

4. A renewable fuse comprising a flat strip having a narrowed fusible intermediate portion and provided at its ends with openings to receive fasteners, and a high resistance wire extending around the fusible portion of 100 said strip and permanently secured at its ends to said strip in electrical engagement therewith, said high resistance wire forming with said strip a single article of manufacture, being adapted to carry a portion of the load while said strip is blowing and being then adapted to fuse, thereby reducing the 105 flash and generation of gases.

In testimony whereof I have hereunto set my hand.

ISRAEL MARCUS.
